UNITED STATES PATENT OFFICE

FREDERICK N. ROSS, OF DETROIT, MICHIGAN

DESIGN FOR AN AIR CIRCULATOR

Application filed December 2, 1932. Serial No. 46,283. Term of patent 14 years.

To all whom it may concern:

Be it known that I, FREDERICK N. Ross, a citizen of the United States, residing at 1010 Beaubien Street, Detroit, in the county of Wayne and State of Michigan, have invented a new, original, and ornamental Design for an Air Circulator, of which the following is a specification, reference being made to the accompanying drawing, forming part thereof.

Fig. 1 is an elevational view of the air circulator showing my new design.

Fig. 2 is a sectional view on line 2—2 of Fig. 1.

Fig. 3 is a top plan view looking in the direction of line 3—3.

I claim:

The ornamental design for an air circulator substantially as shown.

FREDERICK N. ROSS.
